UNITED STATES PATENT OFFICE.

KENNETH RUSHTON, OF PHILADELPHIA, PENNSYLVANIA, ASSIGNEE TO THE BALDWIN LOCOMOTIVE WORKS, OF PHILADELPHIA, PENNSYLVANIA, A CORPORATION OF PENNSYLVANIA.

WEAR-PLATE FOR DRIVING-AXLE BOXES FOR LOCOMOTIVES.

1,345,254.

Specification of Letters Patent. Patented June 29, 1920.

Application filed January 2, 1919. Serial No. 269,249.

To all whom it may concern:

Be it known that I, KENNETH RUSHTON, a citizen of the United States, residing in Philadelphia, Pennsylvania, have invented 5 certain Improvements in Wear-Plates for Driving-Axle Boxes for Locomotives, of which the following is a specification.

My invention relates to certain improvements in wear plates which are located between the rear of the axle box of a locomotive and the wheels and is for the purpose of taking the lateral thrust of the wheel, due to the lateral movement of the axle, which would usually be taken by the box itself. 15 This plate is removable so that, when worn, it can be readily replaced.

One object of the invention is to construct the plate so that it can be readily removed and replaced, and to provide means for holding this plate properly on the box while in use.

A further object of the invention is to construct the plate so that it can be removed from the box without detaching the box from the axle.

These objects I attain in the following manner, reference being had to the accompanying drawing, in which:

Figure 1, is a side view of a car axle box, 30 showing the wheel partly in section and the wear plate located between the box and the hub of the wheel;

Fig. 2, is a sectional view on the line 2—2, Fig. 1;

Fig. 3, is a detached perspective view, showing the two parts of the plate; and

Figs. 4 and 5 are views of modifications.

1 is the axle box of any suitable type located in the frame 2 of the locomotive. 3 is an axle which extends into the box and rests against the bearing block 4 of any ordinary type, the bearing block being shown by dotted lines. Fig. 1. 5 is one of the driving wheels of the locomotive, in the present instance having a hub 6, and located between the hub and the rear end of the box 1 is the wear plate 7. This plate has an oval opening 8, which allows for a certain vertical movement of the axle in the box without affecting the position of the wear plate on the box. The wear plate is made in two sections 9 separated on a vertical line α and has up-

per and lower lugs 10, which project laterally, and openings for the passage of the bolts 11 by which the two sections are 55 clamped together. The upper lugs 10 project over the upper portion 12 of the box 1, while the lower lugs project under the lower portion 13 of the box, and these two lugs hold the box against any vertical movement 60 independently of the box.

In Figs. 1 to 3, I have shown lips 14 at one side of the wear plate, which extend on each side of the box and hold the plate against lateral movement independently of 65 the box, although these lips may be dispensed with in some instances.

In Figs. 4 and 5, I have shown a pin 14^a secured to the back of the box and extending into recesses formed in the two adjoining sections 9. This pin locates the wear plate centrally in respect to the box, the same as the side flanges.

A wear plate constructed in this manner, when worn, can be detached from the box 75 without dismantling any portion of the locomotive and a new plate can be substituted for it without difficulty. A wear plate takes the lateral thrust of the hub of the wheel, due to the lateral movement of the axle in 80 the boxes, and without this wear plate the rear portion of the box would be worn away and the entire box would have to be discarded and a new one substituted for it.

In Figs. 4 and 5, the upper and lower lugs 85 10^a of the section 9^a have lips 15 which extend back of the portions 12^a and 13^a of the box and hold the plate against the box.

I claim:

1. A wear plate for an axle box having an 90 opening for the passage of an axle and made in two sections; perforated lugs at the upper and lower ends of each section; and transverse bolts extending through the perforations and connecting the sections, said lugs 95 extending laterally so as to engage an axle box and acting to locate the wear plate in position on the box.

2. A wear plate adapted to be located between an axle box and the hub of a wheel, 100 said plate having an opening for the passage of an axle and having upper and lower lugs arranged to extend laterally over and under the box; and lips at each side of the

plate and arranged to extend on each side of the box, said plate having transverse bolts by which the two sections are held together.

5 A wear plate for an axle box having an opening for the passage of an axle and made in two sections; perforated lugs at the upper and lower ends of each section; transverse

bolts extending through the perforations and connecting the sections, said lugs extending laterally and having lips to engage 10 an axle box and acting to hold the wear plate in position on the box.

In witness whereof I affix my signature.

KENNETH RUSHTON
